UNITED STATES PATENT OFFICE.

SAMUEL A. KINKEL, OF MINNEAPOLIS, MINNESOTA.

VENTILATOR FOR WINDOW SASHES.

Application filed March 3, 1928. Serial No. 258,827.

It is the object of this invention to provide a novel and improved ventilator, which is particularly adapted for use on storm or window sashes, and is of cheap and of simple construction and may be readily installed.

To this end, the invention consists in the novel parts and novel combinations of parts defined in the claims and described in the following specification made in connection with the accompanying drawings, wherein like reference characters refer to the same or similar parts throughout the various views, and, in which,

Fig. 1 is a view in side elevation of a window sash looking outwardly toward the sash and illustrating an embodiment of the present invention applied to the sash;

Fig. 2 is a horizontal section taken on the line 2—2 of Fig. 1, as is indicated by the arrows;

Fig. 3 is a vertical section taken on the line 3—3 of Fig. 2, as is indicated by the arrows, certain of the parts being illustrated in one position in full lines, and in another position in dotted lines;

Fig. 4 is a vertical section taken on the line 4—4 of Fig. 2, as is indicated by the arrows, and,

Fig. 5 is a view similar to Fig. 3 of a slightly modified form of closure plate which may be used, Figs. 2, 3, 4 and 5 being shown on an enlarged scale.

Referring to the drawings, a window sash 6 having glass panes 7 therein is illustrated and the lower end of the window sash is adapted to abut the sill 8 of a window frame. In accordance with the present invention, a plurality of draft openings 9 are provided through the base of the window sash and these openings project downwardly slightly from the inner side of the window sash to provide a ready drainage for water. A cam sleeve opening 10 is also bored in the base of the window sash from the inner side thereof outwardly to project almost through the sash. In accordance with the present invention, screening 11 is placed over the openings 9 at the inner side of the window sash and an abutment plate 12 is secured to the sash as by nails rearwardly of the screening 11. The abutment plate 12 is substantially rectangular in shape, has openings therethrough in alinement with the openings 9 and 10, and is provided at its

edges with a rearwardly projecting roll 12^a forming, in effect, a rectangular frame, the outer edges of the roll abutting the rear side of the window frame. Secured to the central portion of the forward side of abutment plate 12, and projecting into the opening 10, is a cam 13. This cam has a flat rear portion abutting the plate 12 and is provided with two arms forming a sleeve-like structure which projects into the opening 10. The said arms have forward edges forming cam surfaces and these edges are generally curved diagonally outwardly from the plate 12, and are provided with a plurality of substantially straight portions 13^a forming steps in the cam surfaces and disposed in a plane generally parallel to the plane of the abutment plate 12. A stem 14 projects centrally through the abutment plate 12 and cam 13, and is provided adjacent its forward end with a squared portion having a pin 15 mounted thereon as by means of a nut 16 screwed on to the forward end of the stem. A closure plate 17 is mounted on the stem 14 at the rear side of the abutment plate 12, and the said closure plate is formed in the shape of a casing open at its forward side, the edges of the casing being adapted to strike the abutment plate 12 adjacent the central side of the roll 12^a therein. A coiled spring 18 extends around the stem 14 and reacts between the abutment plate 12 and the forward side of the closure plate. Rearwardly from the closure plate, a handle 19 is formed or secured to the stem 14. In the drawings, the handle 19 is illustrated as being in the shape of a wing nut. Adjacent its two ends, the abutment plate 12 has small U-shaped holders 20 stamped rearwardly therefrom and a bar spring 21, secured to the forward side of closure plate 17, has outer ends fitting through the U-shaped holders for sliding movement therethrough. In Fig. 5, a closure plate 22 is illustrated, which is provided with a forward recessed portion 22^a on its rear side within which the handle 19 on stem 14 may fit, so that the handle will not project for any substantial distance rearwardly from the closure plate.

The two arms of spring 21 will place closure plate 17 under tension to move away from the abutment plate. This movement will be limited by engagement of the pin 15

on the cam surfaces of the cam 13. When the key formed by the handle 19, stem 14 and pin 15 is turned to its extreme clockwise position, as viewed in the drawings, the handle 19 bearing against the rear side of the closure plate, will force the same against the tension of spring 21 and spring 18, so that the edges of the plate strike the abutment plate to prevent passage of air, admitted through the openings 9, between the closure and abutment plates. In this position, the pin 15, as is illustrated in full lines in Fig. 2 and in Fig. 3 of the drawings, will bear against the most forwardly extending portions of the cam 13, and as these portions will form straight steps 13^a set at right angles to the axis of the stem 13, there will be no tendency for the pin 15 to slide away from the cam and, accordingly, the ventilator will be held securely in closed position. When now it is desired to open the ventilator, the handle 19 will be turned in counter clockwise position, thereby permitting the pin 15 to slide down one or more of the diagonally curved portions of the cam surfaces to permit the springs 21 and 18 to force the closure plate 17 rearwardly from the abutment plate, thereby permitting air to pass from the openings 9 and between the closure and the abutment plates. As there are a number of steps 13^a formed on the cam surfaces of the cam 13, it will be apparent that various adjustments of the closure plate relative to the abutment plate can be made, so as to vary the amount of air admitted from between the closure and abutment plates. The two arms of the bar spring 21 will hold both ends of the closure plate under approximately the same tension, so that all points on the edges of the closure plate will be spaced practically the same distance from the abutment plate. The spring 18 will also assist in maintaining even spacing between the edges of the closure plate and the abutment plate. When the closure plate is moved from a closed position, such as is illustrated in full lines Fig. 3, to an open position, such as is illustrated in dotted lines Fig. 3, the outer ends of the spring 21 will, of course, slide within the U-shaped holders 20 on the abutment plate. The screening 11 will prevent the admission of insects and of soot and dirt from the outside. When the closure plate is closed, the roll 12^a will project rearwardly slightly from the edges of the closure plate to shut off any possible draft between the two plates and the roll will also permit the abutment plate to be sprung slightly, due to the action of the cam 13, thereby forming an air tight joint between the closure and abutment plates.

In the form of the device illustrated in Fig. 5, the handle 19 may be held within the recess 22^a on the rear side of the closure plate 22 and, accordingly, the handle 19 will

not be struck to injure the same, or to bend the stem 14 when a number of window sashes, such as storm sashes having the ventilators applied thereto, are stacked one against another.

70

The device has been amply demonstrated in actual practice and provides a very simple, adjustable ventilator, which can be quickly made and readily installed. It will, of course, be understood that various changes may be made in the form, details, arrangement and proportions of the device without departing from the scope of the present invention.

75

What is claimed is:

1. A window ventilator, comprising a plate adapted to fit over an opening in a window sash, resilient means urging said plate away from the sash, a key projecting through said plate and having a head abutting the outer side thereof, and a cam against which portions of said key must travel as it is turned, to force said plate against said sash as the key is turned in one direction and to permit said resilient means to force said plate away from the sash as the key is turned in an opposite direction.

80

2. The structure defined in claim 1, said cam having a plurality of steps formed therein, for releasably engaging said key to hold said plate in any one of a plurality of adjusted positions relative to said sash.

85

3. A window ventilator, comprising a plate adapted to fit over an opening in a window sash, resilient means acting at opposite sides of said plate between the plate and the window sash and urging said plate away from the sash, a key projecting through said plate and having a head abutting the outer side thereof and a cam mounted in said window sash and having portions thereon for determining the movement of said key to and from said sash as the key is turned, whereby as the key is turned in one direction, said plate will be forced toward said window sash and when the key is turned in an opposite direction, said plate will be forced away from said sash by means of said resilient means.

90

4. A window ventilator comprising, an abutment plate having a plurality of apertures therethrough, a sleeve shaped cam secured to the forward side of said abutment plate, a key mounted in said abutment plate and carrying a pin adapted to bear against said cam, a closure plate mounted on said key, said key having a portion abutting the rear side of said closure plate, and resilient means acting between said abutment plate and said closure plate to urge said abutment plate rearwardly from said closure plate, said cam being adapted to act to pull said closure plate towards said abutment plate as said key is turned in one direction.

100

5. The combination with a window sash

115

120

125

130

having a plurality of apertures therethrough, of a window ventilator comprising, an abutment plate mounted on said sash and having apertures therethrough coincident with the 5 apertures through said sash, a cam sleeve secured to the rear side of said abutment plate and projecting into said sash, a closure plate mounted at the rear side of said abutment plate, springs acting between said abutment 10 plate and said closure plate adjacent the ends thereof to urge said closure plate rearwardly from said abutment plate, a stem projecting through said plates and said sleeve and having a head abutting the rear side of said closure plate, and a pin mounted on the forward end of said stem and adapted to bear against the cam portions of said sleeve, whereby as said pin is turned in one direction, said cam sleeve will engage said pin to 15 force said stem and closure plate towards said abutment plate and when said stem is turned in the other direction, said springs 20

will force said closure plate rearwardly from said abutment plate.

6. The structure defined in claim 5, said 25 closure plate having a central portion projecting rearwardly from the rear side thereof, and within which the head of said stem will be mounted.

7. The structure defined in claim 5, said 30 abutment plate having a rolled edge immediately outwardly from the point thereon against which the edges of said closure plate are adapted to strike.

8. The structure defined in claim 5, said 35 sleeve having a pair of arms forming cam portions with a plurality of steps thereon, whereby said pin may be held in any one of a plurality of forwardly projecting positions to vary the adjustment of said closure plate 40 relative to said abutment plate.

In testimony whereof I affix my signature.

SAMUEL A. KINKEL.
